COOLING SYSTEM

Jack M. Thompson, Willimantic, Conn.

Application December 27, 1937, Serial No. 181,958

3 Claims. (Cl. 171—252)

This invention relates to cooling systems and, as illustrated herein, relates more particularly to air cooling and cleansing systems for use in motor vehicles, such as automobiles, airplanes, 5 motorcycles or the like.

An object of the present invention is to provide an improved air cooling system. Another object of the invention is to provide such a cooling system having improved means for delivering and circulating air and cleansing the same. Still another object is to provide an effective system for air cooling generators while at the same time preventing dirt, dust or other foreign substances, which have an injurious abrasive effect upon the 10 rotating parts and bearing surfaces, from circulating within the generator. Still another object of my invention is to provide an improved cooling cap for generators which can be inexpensively manufactured and which can be used to replace non-cooling generator caps now in use. A further object of my invention is to provide such a cap for generators which will effectively prevent abrasive substances from being circulated in the 15 cap and from which the heated air will be effectively withdrawn after it has performed its cooling operation. Still another object of the present invention is to provide improved stationary cooling means for a generator for motor vehicles so located that when the generator is exposed to 20 the action of the air current induced by movement of the vehicle, or by the action of a fan, the air is caused to circulate within these cooling means and the generator casing to cool the generator parts therein, improved means also preferably being provided whereby dust and other foreign substances are prevented from passing to 25 said generator parts. These and other objects of my invention will be apparent from the following description.

In the accompanying drawings I have shown, for purposes of illustration, one embodiment which my invention may assume in practice.

In these drawings:

Figure 1 is a view in side elevation of a vehicle provided with one embodiment of the present invention:

Figure 2 is an enlarged side elevation of the generator shown in Figure 1;

Figure 3 is a view in front elevation of the structure shown in Figure 2;

Figure 4 is a view in rear elevation thereof;

Figure 5 is a view in section on a further enlarged scale, taken along the line 5—5 of Figure 3;

Figure 6 is a view, partly in section, taken along the line 6—6 of Figure 5;

Figure 7 is a perspective view, illustrating the end cap having portions cut away to receive the 5 ventilating members, and

Figure 8 is a perspective view of the ventilating members.

The present invention, as shown in Figure 1, is illustrated as applied to a motorcycle, and it will be noted that a generator 2 is mounted on the 10 upper forward portion of a crankcase 4 of an engine 6, this generator being equipped with my improved cooling means as hereinafter described.

One end of the armature shaft 8, journaled in suitable bearings in the generator casing or housing 9, is connected to the crank shaft of the engine 6 in any suitable manner, for example, by gears or by a chain and sprocket so that an armature 10 mounted thereon may be rotated to produce electrical energy when the engine 6 is 20 operated. The other end of the armature shaft 8 is provided with a commutator 12 which is engaged by brushes mounted in holders 14 and 16, for collecting and transmitting the electrical energy produced, through suitable connections to a 25 storage battery or other electrically controlled or operated devices.

As shown most clearly in Figure 6, the generator casing 9 is open at one end to receive the brush holders 14 and 16 and to permit access 30 thereto. It is usual to provide a cap or cover 18 for this open end. Further due to the exposed location of the generator, it has heretofore been the practice to use a totally closed cap and thereby exclude circulating air from the interior of the 35 generator because of the fact that the air flowing around the generator contains a relatively large amount of dirt, sand, dust and other foreign matter which would have an injurious abrasive effect on the moving parts, causing rapid wear of the 40 same.

This has resulted in other difficulties. Thus, while when a motorcycle or other motor vehicle is stationary, the engine ordinarily is idling and the load on the generator is relatively light, when the 45 vehicle is in motion and, as its speed increases up to approximately twenty-five miles per hour, the charging rate of the generator increases and the brushes of the generator are adjusted to a point where the generator is often heavily overloaded. 50 Motorcycle generators are designed to operate under a load of approximately ten amperes and this ordinarily is sufficient to keep the storage battery on the vehicle fully charged, but it has become a rather usual practice to provide sup- 55

plementary lights, horns and electrically operated or controlled devices so that a charging rate of ten amperes is not sufficient to keep the storage battery fully charged. To keep the battery fully charged, the charging rate of the generator is increased to eighteen or twenty amperes. This, of course, causes the generator to heat excessively unless some means is used to cool the generator. In fact, the temperature of a generator equipped with the usual closed cap, often reaches 190° F. or more, with the result that the armature burns out after a relatively short period of use.

To avoid this difficulty, I provide improved cooling means adapted to take advantage of the fact that the generator 2 is mounted on the motorcycle forwardly of the engine 6 so that the end of the generator carrying the cover 18 is exposed to the action of a stream of cool air when the motorcycle is in motion. Further, although the generator 2 is stationary relatively to the motorcycle and the engine 6 on which it is mounted, I have provided improved means for utilizing this cool air stream so that the parts of the generator 2 will be effectively cooled when the generator is operating under a heavy load.

The present invention provides improved means for permitting air to enter the cover 18 and circulate therein, and thus cool the heated parts while at the same time trapping and discharging foreign matter contained in the air to prevent such foreign matter from injuring the moving parts and bearing surfaces of the generator. The cover, 18, is provided with a convex end portion 19. This end portion is suitably recessed, herein at diametrically opposed points 21 and 23, to provide seats for the cap 18 when it is placed in operative position over the end of the casing 9 of the generator, and each recessed portion 21 and 23 has a hole therein to receive a suitable screw 18a for securing the cap or cover 18 in operative position on the generator. The lower portion or side of the cover 18 is cut away as shown at 24 in Figure 7 to form an opening adapted to receive a curved plate 22 which is brazed, welded or otherwise suitably secured to the cover 18. The curved plate 22 is formed with a plurality of hoods or openings 24 on the bottom of the plate, which are so arranged that they are directed forwardly into the path of movement of a current of air. The openings 24 are formed in the plate 22 by cutting three slits in the plate and then raising the portions 25 of the plate behind these slits. It is to be noted that the openings 24 are offset with respect to each other to insure that each opening will be unobstructed to permit the maximum amount of air to enter the same. These openings 24 are covered by screens 26 which remove the larger particles of dust, sand or other foreign matter from the air which is to enter the cover 18 but which do not remove all harmful abrasive foreign matter which would produce excessive wear on the bearings and moving parts of the generator if allowed to come into contact therewith. Some of the remaining foreign material adheres to the inside portion of the plate 22 and to remove the remaining foreign matter, a deflecting member or plate 28 is provided in the rear portion of the plate 22. This extends inwardly and downwardly at an angle of approximately 45° to the tangent to cause other particles of dirt or other foreign matter to be deflected downwardly and outwardly through a narrow slot 30 formed in the plate 22. Due to the relatively high speed at which the air is forced through the openings 24, the

relatively heavy particles of dust, sand and other foreign matter, tend to move in a straight line along the inside surface of the plate 22 and between the latter and the adjacent portions 22a of the cover 18 in such manner as to be kept out of the generator brushes and delivered through the opening 20 substantially within the vertical limits of the deflector 28. Consequently, the greater portion of these particles is trapped by the deflecting or baffle plate 28 and discharged through the narrow slot 30. The remaining cleaned portion of the air which has entered the openings 24 is free to circulate within the casing 17 and the cover 18 to cool the heated parts.

The cover 18 is also provided opposite the opening 20, with a V-shaped opening 32 which is adapted to receive a plate 34, welded, brazed or otherwise suitably secured to the cover 18 over the opening 32. The plate 34 is curved transversely at its rear end so that a rearwardly directed opening 36 is formed between the plate 34 and the cover 18. The opening 36 may, as illustrated, be covered by a screen 38. After the air has circulated within the casing, as above described, it passes through the V-shaped opening 32 and then through the opening 36. The circulation of the air is facilitated by the fact that when a motor vehicle is traveling at a relatively high rate of speed, a partial vacuum is created behind the opening 36. This partial vacuum causes the air contained in the casing to move therethrough much faster than would otherwise normally occur. It is to be noted that the parts above referred to are stationary relatively to each other, to the generator on which they are mounted, and to the engine 6 on which the generator is mounted. Considerable air pressure is set up when the motorcycle is in motion which will cause the air received by the apertures 24 to be circulated within the generator casing and the exhaust aperture 36 will cooperate therewith to circulate and to deliver the air from the casing 9.

It is to be noted that the combined area of the apertures or openings 24 is slightly less than the area of the exhaust aperture 36. If the combined area of the openings 24 is too great, undesirable currents of air will be set up inside of the generator which would prevent effective trapping and discharging of foreign matter by the deflecting or baffle plate 28. On the other hand, if the exhaust aperture 36 is too large as compared to the openings 24, the air will be circulated through the interior of the generator at such a high rate of speed that effective trapping and discharging of foreign matter through the slot 30 would not take place. The slot 30 must also be of a predetermined size to insure that foreign matter will be effectively discharged. It has been found that the combined area of the slot 30 and the openings 24 should be substantially equal to the area of the exhaust opening 36 and that the area of the slot 30 should be approximately one-third of the combined area of the openings 24 to produce the most satisfactory results. It is to be understood, however, that these proportions may be varied depending upon the conditions under which the generator is used.

In the illustrated embodiment of the invention, the air is caused to circulate only about the commutator and the adjacent end of the armature. This has been found sufficient to reduce the temperature of the armature approximately 30 per cent. It is evident, however, that the

air could circulate about the whole armature if desired. A portion of the armature, about which the air does not circulate to any marked degree, is cooled by conduction. The field windings of the generator are cooled to a great extent by the movement of air about the outside of the casing 9.

After the cap or cover 18 has been assembled, it is placed on the generator 2 and secured in position with the apertures 24 directed into the path of movement of the current of air. As illustrated, the generator 2 is disposed with its axis substantially at right angles to the path of movement of the motorcycle but it is apparent that, in other vehicles, the axis of the generator could be disposed at other angles to the path of movement, depending upon the direction of the movement of the air to the generator. It is desirable that the openings 24 should be positioned substantially right angles to the path of movement of the current of air, to produce the best results.

It is apparent that, with the above arrangement, the air which enters the generator casing is free from dust or foreign matter and that this is accomplished while obtaining a flow of air of large volume into the generator casing and through the latter. Furthermore, the cap 18 is inexpensive to manufacture and, consequently, does not materially increase the cost of the generator. By the use of the cap or cover 18, above described, the operating temperature can be decreased by as much as 30 per cent which will aid materially in increasing the life of the generator and in reducing the expense of operating the vehicle.

Although the invention has been described and illustrated as applied to a motorcycle, it is evident that it could also be used in other motor vehicles or applied to generators operated by stationary engines where the air is caused to flow past the generator by the use of a fan or other suitable means. Moreover, it will be evident that my improved structure may also be applied to use on motors of various types, and on other parts which it is desired to air cool, or air cool while cleansing the air, such as other parts of an automobile, motorcycle, or airplane, which tend to heat in operation while air flow is available to cool the same. For example, where the landing fields are dusty, the conditions surrounding the use of airplane equipment are closely similar to those in a motorcycle. Also, while my improved cap has been described and shown as formed of a plurality of parts, it is evident that the cap could be formed in one part if it were found desirable or economical to do so.

While I have in this application specifically described only one embodiment of my invention, it will be understood that this embodiment is shown for purposes of illustration, and that the invention may be modified without departing from its spirit or the scope of the appended claims.

What I claim as new and desire to secure by Letters Patent is:

1. In a cooling cap for generators having a generally cylindrical generator casing arranged in an external air stream set up by bodily movement of the generator, a generally cylindrical cap adapted to enclose one end of said casing and spaced from said casing to form an annular chamber therewith, passage forming means on said cap disposed tangentially thereof close to the outer periphery thereof and opening transversely to the generator axis and directing air

from said air stream tangentially into said cap along the inner wall thereof, tangentially disposed exhaust passage forming means on said cap close to the outer periphery thereof and oppositely directed relative to said inlet passage forming means and opening transversely to the generator axis on the opposite side of said cap from said inlet passage forming means for sucking air tangentially from adjacent the inner wall of said cap and cooperating with said inlet passage forming means to set up an air flow through said cap between said inlet and exhaust passage forming means, means for separating the larger foreign particles from the air entering said cap, and means within said chamber for separating smaller foreign particles from the entering air stream and discharging the same into the outside air stream.

2. A generator cooling system arranged in an external air stream set up by bodily movement of the generator comprising in combination, a generally cylindrical generator casing, a cylindrical cap enclosing one end thereof and spaced from said casing to form an annular chamber therewith, passage forming means on said cap disposed tangentially thereof close to the outer periphery thereof and opening transversely to the generator axis and directing air from said air stream tangentially into said cap along the inner wall thereof, tangentially disposed exhaust passage forming means on said cap close to the outer periphery thereof and oppositely directed relative to said inlet passage forming means and opening transversely to the generator axis on the opposite side of said cap from said inlet passage forming means for sucking air tangentially from adjacent the inner wall of said cap and cooperating with said inlet passage forming means to set up an air flow through said cap between said inlet and exhaust passage forming means, means for separating the larger foreign particles from the entering air, and means within said chamber for separating smaller foreign particles from the entering air stream and discharging the same into the outside air stream.

3. A generator cooling system adapted to be responsive to an external air stream flowing in a radial direction to the generator comprising in combination, an electrical generator of cylindrical form having a cap enclosing one end thereof, inlet passage forming means on said cap disposed tangentially thereof close to the outer periphery thereof and opening transversely to the generator axis and directing air from said air stream tangentially into said cap along the inner wall thereof, and tangentially disposed exhaust passage forming means on said cap close to the outer periphery thereof and oppositely directed relative to said inlet passage forming means and opening transversely to the generator axis on the opposite side of said cap from said inlet passage forming means for sucking air tangentially from adjacent the inner wall of said cap and cooperating with said inlet passage forming means to set up an air flow through said cap between said inlet and exhaust passage forming means, said cap having an air inlet aperture enclosed by said tangential inlet passage forming means, and means including a member projecting transversely of the air stream flowing into said aperture for separating and discharging from said cap foreign particles in said entering air stream.

JACK M. THOMPSON.
